(57) **CLAIM**

The ornamental design for a fuel can, as shown and described.

DESCRIPTION

Fig. 1.1 shows a side view of a fuel can according to the invention;

Fig. 1.2 shows a side perspective view thereof;

Fig. 1.3 shows a bottom view thereof;

Fig. 1.4 shows an elevated side view thereof;

Fig. 1.5 shows a top plan view thereof;

Fig. 1.6 shows a top perspective view thereof; and

Fig. 1.7 shows a back view thereof.
